CLAIM

The ornamental design for a flamingo-bill hair clip, as shown and described.

DESCRIPTION

FIG. 1 is a right side elevational view of a flamingo-bill hair clip according to the present invention, the left side elevational view being mirror symmetric with that of FIG. 1;

FIG. 2 is a top plan view thereof;

FIG. 3 is a rear elevational view thereof;

FIG. 4 is a front elevational view thereof; and,

FIG. 5 is a bottom plan view thereof.
